The ornamental design for a spacer for beverage brewing apparatus, as shown and described.

DESCRIPTION

FIG. 1 is a front, perspective view of the spacer for beverage brewing apparatus of the instant invention.

FIG. 2 is a top plan view of the spacer for beverage brewing apparatus of the instant invention.

FIG. 3 is a bottom plan view of the spacer for beverage brewing apparatus of the instant invention.

FIG. 4 is a front elevational view of the spacer for beverage brewing apparatus of the instant invention.

FIG. 5 is a rear elevational view of the spacer for beverage brewing apparatus of the instant invention.

FIG. 6 is a side elevational view of the spacer for beverage brewing apparatus of the instant invention. The opposite side is the mirror image.
